[57] CLAIM

The ornamental design for a construction toy door block, as shown and described.

DESCRIPTION

FIG. 1 is a front perspective view of a construction toy door block, with the door which fits into the center of the construction toy door block exploded out, embodying my new design.

FIG. 2 is a front perspective view thereof;

FIG. 3 is a front elevational view thereof.

FIG. 4 is a rear elevational view thereof.

FIG. 5 is a top plan view thereof; the bottom plan view being a mirror image.

FIG. 6 is a right side elevational view thereof; the opposite side being a mirror image.

FIG. 5

FIG. 3

FIG. 6

FIG. 4
